UNITED STATES PATENT OFFICE.

ERNEST L. B. ZIMMER, OF OAKLAND, CALIFORNIA, ASSIGNOR OF SEVENTY-FOUR ONE-HUNDREDTHS TO JOHN WESLEY HURLEY, OF PORTLAND, OREGON.

SELF-CLEANING BAG FOR VACUUM-CLEANERS.

1,176,721.

Specification of Letters Patent. Patented Mar. 21, 1916.

Application filed June 2, 1915. Serial No. 31,756.

To all whom it may concern:

Be it known that I, ERNEST L. B. ZIMMER, a citizen of the United States, residing at Oakland, in the county of Alameda and State of California, have invented new and useful Improvements in Self-Cleaning Bags for Vacuum-Cleaners, of which the following is a specification.

This invention relates to improvements in 10 dust bags for vacuum cleaners and the like, and particularly to a self-cleaning dust bag and holder therefor.

One of the objects of the present invention is to provide a simple, durable, cheaply manufactured dust bag which is so constructed 15 that vibration or movement in all directions will be transmitted to the bag, when in operation, thus producing a self-cleaning action and also preventing excessive accumulations of dust on the surface of the bag at 20 any time.

Another object of the invention is to place a perforated weighted bottom interiorly of the bag to keep it stretched and to place a 25 plurality of flexible members interiorly of the bag which are connected at their upper ends with the bag support and at their lower ends with the perforated bottom; and to provide a striking head with which said 30 members engage when the bag is contracted by the suction stroke of the connected pump.

Further objects will hereinafter appear.

The invention consists of the parts and the construction and combination of parts 35 as hereinafter more fully described and claimed, having reference to the accompanying drawings, in which—

Figure 1 is a perspective view of the bag frame. Fig. 2 is a side elevation showing 40 the bag mounted in the dust collecting tank. Fig. 3 is an enlarged sectional view of the lower end of pipe 10.

A indicates a head which forms a closure 45 for the dust collecting receptacle or tank, such as indicated at B. Formed on the lower side of said head is an annular, downwardly projecting flange 2, on the lower edge of which is formed a plurality of perforated lugs 3. Pivotaly mounted and ex- 50 tending downwardly from said lugs is a plurality of flexible wire rods 4, and suspended from the lower ends of said rods is a perforated weighted bottom section 5.

The upper face of said bottom is provided 55 with a plurality of perforated lugs 6, similar

to the lugs 3, and the rods are pivotally secured in same. The bottom section 5 is thus suspended from the several rods 4 and is free to swing in any direction.

Formed on each wire rod 4, intermediate 60 of the ends, is a coiled section 7. This is provided for the purpose of producing greater flexibility and also for the purpose of transmitting the greatest vibratory movement possible to the dust bag 8 which is 65 mounted exteriorly of the bottom section 5 and rods 4; the upper end of the bag being slipped over the exterior face of flange 2 and being secured thereto by a clamp ring of suitable construction, such as indicated at 9. 70

Centrally secured in the head 2 and extending downwardly a suitable distance between the rods 4 is a tube 10, on the lower end of which is mounted a collar 11 which will hereinafter be known as the "striking 75 cam". The lower end of the tube is provided with a plurality of openings, such as indicated at 12, and these, together with the lower end of the tube, are covered with a finely woven wire fabric or screen material, 80 such as indicated at 13.

In operation, it is only necessary to insert the bag frame as a whole into the tank indicated at B and to secure the head on the tank by means of screws or the like to form an 85 air-tight connection at this point. Pipe 14 is then connected with a vacuum pump (not here shown) and as this pipe connects with the tube 10 it will be seen that a vacuum will be produced interiorly of the bag and 90 tank B.

15 indicates a pipe to which the suction hose and cleaning apparatus may be attached and 16 a suitable form of opening through which the dust may be removed 95 from the tank. The moment suction is applied to pipe 14 it will immediately be transmitted through central tube 10 and the screened openings formed in the lower end thereof. A vacuum will thus be produced 100 within the bag and this is in turn transmitted to the interior of tank B and pipe 12. The dust entering through the suction hose with the incoming air, when the apparatus is being used, will thus enter tank B and will 105 consequently have a tendency to collect on the outer face of the bag. Any accumulation or caking of dust on the exterior face of the bag is, however, prevented by the automatic vibratory action of the, flexible rods 110

4. The pulsations transmitted from the pump will have a tendency to continuously contract and expand the surface of the bag, together with the flexible rods 4, in a radial 5 direction inwardly and outwardly. The surface of the bag is thus constantly vibrated radially and also longitudinally, as the inward movement of the rods has a tendency to lift the weighted bottom section 5 upwardly. The bottom section 5 is thus constantly jumping up and down, thereby transmitting a longitudinal shaking motion to the bag in unison with the radial vibration transmitted through rods 4. The inward 10 movement of the rods is limited by the striking head 11, as the coiled sections 7 engage same when contracted by the suction stroke of the pump. The surface of the bag is thus vibrated on the inward movement 15 of the rods when these engage the striking head and the surface of the bag is also vibrated when the wire rods are relaxed on their outward movement.

It sometimes happens that the canvas bag 25 will crack or rip due to wear and tear or other causes. The dust will then enter directly through pipe 10 into the pump with a consequent ruinous action. This danger is, however, eliminated in the present instance 30 by providing the screened openings 12.

A dust bag constructed and mounted in the manner here shown is simple, durable, and highly efficient in action. It not only presents a large filtering surface with a subsequent 35 reduction of pull on the pump, but being automatically vibrated, both radially and longitudinally, it is absolutely self-cleaning in action, thus reducing a pull on the pump to a minimum.

40 The materials and finish of the several parts of the device are such as the experience and judgment of the manufacturer may dictate.

Having thus described my invention, what 45 I claim and desire to secure by Letters Patent is—

1. In an apparatus of the class described, a bag frame comprising a head, a bottom section, a plurality of flexible suspension members supporting the bottom section, and a dust bag secured exteriorly of the frame 50 forming a covering for the flexible suspension members and bottom section.

2. In an apparatus of the class described, 55 a bag frame comprising a head, a bottom section, a plurality of flexible suspension members supporting the bottom section with relation to the head, and a dust bag secured to the head and forming an exterior covering for the flexible suspension members and bottom section.

3. In an apparatus of the class described, 60 a bag frame comprising a head, a plurality of wires pivotally connected at their upper ends with the head, a bottom section pivot-

ally suspended from the lower ends of said wires, and a dust bag secured to the head and forming an exterior covering for the wires and bottom section.

4. In an apparatus of the class described, 70 a bag frame comprising a head, a plurality of wires pivotally connected at their upper ends with the head, a bottom section pivotally suspended from the lower ends of said wires, a coil section formed on each wire intermediate of its ends, and a dust bag secured to the head and forming an exterior covering for the wires and bottom section. 75

5. In an apparatus of the class described, 80 a bag frame comprising a head; a bottom section, a plurality of flexible suspension members supporting the bottom section with relation to the head, a dust bag secured to the head and forming an exterior covering 85 for the flexible suspension members and bottom section, and a striking head centrally disposed interiorly of the flexible suspension members and bag with which the flexible suspension members engage when they are contracted by suction.

6. In an apparatus of the class described, 90 a bag frame comprising a head, a plurality of wires pivotally connected at their upper ends with the head, a bottom section pivotally suspended from the lower ends of said wires, a dust bag secured to the head and forming an exterior covering for the wires and bottom section, and a striking head centrally disposed interiorly of the wires and bag with which they engage when the bag 95 and wires are contracted radially by suction. 100

7. In an apparatus of the class described, 105 a bag frame comprising a head, a plurality of wires pivotally connected at their upper ends with the head, a bottom section pivotally suspended from the lower ends of said wires, a coil section formed on each wire intermediate of its ends, a dust bag secured to the head and forming an exterior covering 110 for the wires and bottom section, and a striking head centrally disposed between the coil sections.

8. In an apparatus of the class described, 115 a bag frame comprising a head, a bottom section, a plurality of flexible suspension members supporting the bottom section with relation to the head, a dust bag secured to the head and forming an exterior covering for the flexible suspension members and bottom section, a tube centrally secured in the head and extending downwardly between the flexible suspension members, and a screen covering the end of said tube. 120

9. In an apparatus of the class described, 125 a bag frame comprising a head, a bottom section, a plurality of flexible suspension members supporting the bottom section with relation to the head, a dust bag secured to the head and forming an exterior covering 130

for the flexible suspension members and bottom section, a tube centrally secured in the head and extending downwardly between the flexible suspension members, a screen covering the end of said tube, and a striking head mounted on the tube.

10. In an apparatus of the class described, a bag frame comprising a head, a plurality of wires pivotally connected at their upper ends with the head, a bottom section pivotally suspended from the lower ends of said wires, a coil section formed on each wire intermediate of its ends, a dust bag secured to the head and forming an exterior covering for the wires and bottom section, a tube centrally secured in the head and extending downwardly between the flexible suspension members, a screen covering the end of said tube, and a striking head mounted on the tube with which the coil sections engage when the bag is contracted radially by suction.
- 15 for the wires and bottom section, a tube centrally secured in the head and extending downwardly between the flexible suspension members, and a screen covering the end of said tube.
- 20 11. In an apparatus of the class described, a bag frame comprising a head, a plurality

of wires pivotally connected at their upper ends with the head, a bottom section pivotally suspended from the lower ends of said wires, a coil section formed on each wire intermediate of its ends, a dust bag secured to the head and forming an exterior covering for the wires and bottom section, a tube centrally secured in the head and extending downwardly between the flexible suspension members, a screen covering the end of said tube, and a striking head mounted on the tube with which the coil sections engage when the bag is contracted radially by suction. 25
